UNITED STATES PATENT OFFICE

WALTER BERNHEIM KAUFFMANN, OF BOSTON, MASSACHUSETTS, ASSIGNOR, BY
MESNE ASSIGNMENTS, TO EDWARD S. FOSTER, OF BOSTON, MASSACHUSETTS

METAL DISH TRAY FOR DISHWASHING MACHINES

Application filed January 28, 1928. Serial No. 250,131.

This invention relates to improvements in metal dish trays and more particularly to that type of metal dish tray used in connection with dish washing machines.

5 One of the objects of the invention is to provide a tray of this type which is so constructed as to allow the placing of the dishes or the like, to be washed, in the tray in such a manner that they will not come into contact with each other during the washing operation.

A further object of the invention is to provide a tray of this type so constructed that dishes or the like placed therein will be subjected to a minimum contact with metal parts of the tray.

A further object of the invention is to provide a metal dish tray for dish washing machines so constructed that a number of trays 20 may be placed one on top of each other during the working operation or afterwards without the parts of any one tray coming in contact with the dishes or the like placed in the next adjacent tray.

25 A further object of the invention is to provide a construction of metal dish tray whereby provision is made to permit the water sprays of a washing machine to strike all parts of the dishes being washed and to allow the water from said sprays to quickly leave the tray after the washing operation has been completed.

A further object includes the provision of means for allowing the rapid replacing of 35 certain parts of the tray in case of breakage thereof. My invention provides a tray constructed with compartments of such size as to allow the placing of cups, glasses and other dishes therein, each compartment accommodating as a unit the individual cup, glass or other dish thereby preventing the same from coming in contact with each other or with the metal to prevent breaking when the tray is used for washing dishes. The construction 40 of the tray is further also adapted for the storing of the dishes without removing the same from the tray. The bottom of the tray is so constructed that the cups, glasses and other dishes rest on wooden fiber or other 50 composition rods or dowels, thereby prevent-

ing the dishes from becoming marked or discolored. The construction of the tray allows for replacement of said rods or dowels in the event that one or more should become broken. A suitable collar is provided to fasten the 55 dowels in position. This may be a ring or collar or a spring wire or metal clip.

Other objects of the invention will be apparent from the following description of the preferred form of embodiment of my invention which is illustrated in the accompanying drawings forming part of this specification.

In the drawings,

Figure 1 is a plan view of a construction 65 embodying the principles of my invention;

Fig. 2 is an end view thereof;

Fig. 3 is a sectional view taken on the line N—N Figure 1, looking in the direction of the arrows;

Fig. 4 is a sectional view taken on the line x—x Figure 1, looking in the direction of the arrows; and

Fig. 5 is an enlarged view of one end of Figure 3.

Like numerals refer to similar parts throughout the several views.

Referring now to the drawings, the tray is composed of the four side portions or walls 1, 2, 3 and 4 which are made of any suitable metal and have a plurality of perforations therein indicated at 5. The upper and lower edges of the side portions are reinforced by metal strips 6 and 7 which are adapted to be bent over the edges of the side portion and are secured thereto by rivets or other suitable means.

The corners of the tray formed by the joiner of the side portions are further reinforced by having secured thereto the metal angle pieces 8, 9, 10 and 11. These angle pieces project a distance above the upper edge of the side portions 1, 2, 3 and 4 and the said upwardly projecting portion of each of the angle pieces is bent outwardly as at 12, so as to form an angular recess adapted to receive one of the corners formed by the lower edges of the side portions of another similarly constructed tray when said tray is placed on top thereof.

The sides 1 and 2 of the tray are provided with openings 13 and 14 to allow the insertion of the fingers to lift or carry the tray.

Positioned at equal distances apart and secured at their ends to the side portions 2 and 4 are the perforated metal spacing members 13, 14 and 15. The upper and lower edges of the spacing members 13, 14 and 15 are reinforced by metal strips 16 and 17 which are bent over the edges and secured to the same in any suitable manner. The spacing members 13, 14 and 15 are less in width than the side portions 1, 2 and 3.

The reinforcing strips 16 of the metal spacing members 13, 14 and 15 are provided with openings adapted to receive the metal spacing rods 20, 21 and 22 which are secured at their ends to the reinforcing strips 6 of the side portions 1 and 3.

The side portions 1 and 3 and the reinforcing strips 17 of the spacing members 13, 14 and 15 are also provided with openings therethrough adapted to receive the wooden rods 18. The side portions and spacing members 25 are also provided with openings to receive the wooden buffer rods 19.

The rods 18 extend across the tray and are disposed parallel with each other and spaced a predetermined distance apart and above the bottom edge of the tray. The rods 19 are disposed across the tray and parallel with each other and rods 18 and are positioned a predetermined distance above rods 18 and directly under the metal spacing rods 20, 21 and 22. The rods or dowels 18 and 19 are of a greater circumference than the metal rods 20, 21 and 22 and are of wood or fiber to prevent breakage or staining.

The wooden rods 18 and 19 are prevented from slipping out of position by means of collars 23 on the inner sides of opposite side walls, as the walls 1 and 3. In these collars rods 18 and 19 are detachably secured by any suitable means such as by screws 24.

It will be seen by the above construction and arrangement of the parts there is provided a tray adaptable for use in dish washing machines which is divided up into compartments in which individual dishes or cups, such as is indicated by the numeral 25 in Figure 1, may be placed and said dish or cup will be supported upon the wooden rods 18 extending across the tray and the dish or cup will not have contact with any of the metal portions of the tray except the perforated spacer members 13, 14 and 15. The wooden rods 19 prevent the dish or cup from striking the metal rods 20, 21 or 22 because said wooden rods are of larger circumference than said metal rods and, therefore, will save the dish or cup from striking the metal rods.

The fact that the wooden supporting rods 18 are positioned a considerable distance above the lower edge of the tray allows the

nesting of the trays in the angular corner recesses formed in the angle pieces 9, one above the other without the dishes or cups in any particular tray coming in contact with the dishes of its next adjacent tray.

The position of the rods 18 and 19 for supporting and spacing the dishes in the tray also allows the free access of the water sprays of the washing machine to the dishes to be washed and allows the water to immediately drain off from said dishes and away from the tray.

The perforated sides of the tray and the perforated spacing members 15 also facilitate the quick draining off of the water after the dishes have been subjected to the spraying process.

Having now described my invention, what I claim as new and useful, of my own invention, and desire to secure by Letters Patent is:

1. In a rectangular tray construction for use in dish washing machines, the combination of perforated metal side members having their upper and lower edges reinforced by metal strips secured thereto, metal reinforcing plates secured to the corners formed by the joinder of said side members with each other, a plurality of perforated metal spacing strips of less width than said side members, and secured to and extending at predetermined intervals between two of said side members, metal reinforcing strips secured to the upper and lower edges of said metal spacing strips, a plurality of metal spacing rods secured to the upper reinforced portions of and extending between the other two side members and said metal spacing strips, and a plurality of parallel wooden rods spaced at predetermined intervals with respect to each other and removably supported by and extending through said last mentioned side members and the lower reinforced portions of said metal spacing strips.

2. In a tray construction for use in dish washing machines, the combination of perforated metal side members having reinforced edges, reinforcing plates secured to the corners formed by the joinder of said side members with each other, said reinforcing plates extending above the upper edges of said side member and formed so as to provide a seat for receiving the bottom corners of a similar tray, a plurality of perforated metal strips of less width than the perforated metal side members of the tray, and secured to and extending at predetermined intervals between two of said side members so that the upper edges of the said spacing strips are flush with the upper edges of said side members, a plurality of metal spacing rods secured to and extending at predetermined intervals between the other two side members and passing through the upper portions of said spacing strips, a plurality of parallel wooden rods disposed at predetermined intervals with re-

spect to each other and removably supported by and extending through the last mentioned side members and the lower portions of said spacing strips and a plurality of parallel wooden rods removably supported by and extending through said side members and perforated spacing strips and disposed above and at predetermined intervals from said first mentioned wooden rods and from each other.

3. In a rectangular tray construction for use in dish washing machines, the combination of metal perforated side members having reinforced upper and lower edges, metal reinforcing plates secured to the corners of said tray, said reinforcing plates extending above the upper edges of the side members and shaped to form a seat to receive the bottom corners of a similar shaped tray, a plurality of perforated metal spacing members of less width than said side members and having reinforced upper and lower edges, said spacing members secured to and extending at predetermined intervals between two of said side members, a plurality of metal spacing rods secured to the upper portions of and extending between the other two side members and said metal spacing strips, a plurality of removable wooden rods of larger diameter than said metal spacing rods and spaced at predetermined intervals with respect to each other and extending through said last mentioned side members and the lower reinforced portions of said perforated strips, a plurality of removable wooden rods of the same diameter positioned above, parallel to and a predetermined distance from, said first mentioned wooden rods and extending through the same side members and perforated spacing strips, and means for securing said rods in fixed position with respect to said side members and spacing strips.

4. In a tray construction for use in dish washing machines, the combination of perforated side members, a plurality of perforated spacing members equidistantly disposed between two of said side members, a plurality of spacing rods equidistantly disposed transversely of said spacing members and between the other two side members, a plurality of removable wooden rods supported by and extending through the last mentioned side members and said perforated spacing members, said wooden rods being spaced a predetermined distance apart, means for securing said rods in fixed position with respect to said side members and spacing strips and means secured to the upper corners of said tray for receiving and retaining the corners of a similar tray when said similar tray is placed on top thereof.

In testimony whereof I have hereunto set my hand on this 24th day of January, A. D. 1928.

65 WALTER BERNHEIM KAUFFMANN.
